F. JERDONE, JR.,
FUEL RESERVE SUPPLY SYSTEM FOR SELF PROPELLED VEHICLES.
APPLICATION FILED MAY 26, 1919.

1,397,523.

Patented Nov. 22, 1921.

UNITED STATES PATENT OFFICE.

FRANCIS JERDONE, JR., OF TOLEDO, OHIO, ASSIGNOR TO THE WILLYS-OVERLAND COMPANY, OF TOLEDO, OHIO, A CORPORATION OF OHIO.

FUEL-RESERVE-SUPPLY SYSTEM FOR SELF-PROPELLED VEHICLES.

1,397,523.

Specification of Letters Patent.

Patented Nov. 22, 1921.

Application filed May 26, 1919. Serial No. 299,863.

To all whom it may concern:

Be it known that I, FRANCIS JERDONE, Jr., residing at Toledo, county of Lucas, State of Ohio, have invented certain new and useful Improvements in Fuel-Reserve-Supply Systems for Self-Propelled Vehicles, of which I declare the following to be a full, clear, and exact description.

My invention relates to a fuel reserve supply system for self propelled vehicles, and has for its object to provide simple and inexpensive means by which a reserve supply of fuel may be maintained in the main fuel supply tank, from which the fuel is fed to the engine.

Another object of the invention is to provide improved means adapted to be connected in the vacuum fuel feed system of an internal combustion engine, which will automatically stop the flow of fuel from the main fuel supply tank when the fuel therein has been reduced to a predetermined amount.

Another object of the invention is to provide improved means for controlling the discharge of fuel from a receptacle, said means being adapted for connection with any suitable form of aspirator, and arranged to extend into said receptacle to automatically stop the flow of fuel therefrom when it reaches a predetermined level therein.

Still another object of the invention is to provide an improved liquid control device comprising an air tight closure arranged to be connected with an aspirator and adapted to be inserted in a liquid holding receptacle, and carrying means which will serve to automatically stop the flow of liquid from the receptacle when it falls below a predetermined level therein, said means being adjustable to permit the use of the liquid in the receptacle below said level and being adapted to move automatically from said adjusted position when the liquid in the receptacle rises slightly above said level.

To these and other ends the invention comprises certain novel features of construction and arrangement of parts, as will be hereinafter more fully pointed out and claimed, it being understood that the construction is susceptible to various modifications not shown in the drawings without departing from the spirit of the invention, as expressed in the claims.

A structure constituting one embodiment of my invention is illustrated in the accom-

panying drawings forming a part of this specification, in which:

Figure I is a diagrammatic view illustrating the manner of connecting the device with the vacuum fuel feed system of an internal combustion engine.

Fig. II is a sectional elevation of the invention showing the fuel control valve in closed position.

Fig. III is a similar view with the valve shown in open position.

Fig. IV is an enlarged detailed fragmentary section taken through the lower end of the suction tube and valve shown in Fig. II, and

Fig. V is a detailed perspective view of a spring serving as a guide and holder for the valve rod as shown in Fig. III.

Similar reference numerals refer to similar parts throughout the several views of the drawing.

Referring to the drawings, 10 represents an internal combustion engine having a carburetor 11 and an intake manifold 12. A vacuum feed tank 13 is connected with said carburetor and manifold by means of conduits 14 and 15 respectively, while the main fuel supply tank 16 is connected with said vacuum tank by means of a conduit 17, as shown in Fig. I. The parts just described are intended to represent diagrammatically a suitable vacuum fuel feed system for conveying fuel from the main fuel supply tank to the carburetor of the engine in a well known manner. In carrying out the present invention a tube or casing 46 is threaded into the upper wall of the tank 16 as indicated at 47, and is provided with a downwardly extending reduced tubular portion 48 having a plug 49 in the lower end thereof provided with a fuel inlet opening adapted to be closed by a valve 50 on the stem 51, which extends upwardly through said tubular portion 48 into the enlarged portion 46 of the tube, where it is provided with a laterally extending portion 52 adapted to engage the spring holder 53 in the notch 54 at the upper end thereof when it is desired to hold the valve in open position as shown in Fig. III.

A head 55 on the lateral portion 52 of the rod serves to prevent displacement of the spring until such time as said lateral portion is lifted out of the notch 54 to effect the release of the rod in a manner which will presently be described. The spring 53 is

bent upon itself as indicated at 56 and is secured to the bottom of the casing 46 by means of a screw 57, the bent portion 56 being extended as indicated at 58 and provided with an opening 59 through which the rod 51 extends and by which it is guided to move centrally of the tube 48 when shifted longitudinally therein. A float 60 is mounted to travel upon the tube 48 exteriorly thereof and is provided with a downwardly extending yoke 61 having outwardly bent ends 62 connected with the float 60 by means of the bolts 63 as shown in Fig. II. The lower transverse portion 64 of the yoke is provided with an opening adapted to receive a hook bolt or screw 65 of considerably less diameter than the opening, said screw being extended upwardly into threaded engagement with the stem 66 of the valve 50 as shown in Fig. IV. The valve 50 is connected with the stem 51 preferably by a reduced threaded portion 67 screwed into the upper face of the valve centrally thereof. The opening 68 in the transverse portion 64 of the yoke is slightly larger in diameter than the fuel inlet opening in the plug 49, and although said transverse portion 64 may be carried upwardly by the float 60 until it engages the bottom of the tube 48, it will not prevent the flow of fuel through the tube as the hook bolt 65 is relatively small in diameter and does not affect or prevent the flow of fuel through said opening 68. The bolt 65 which forms a continuation of the valve stem serves to permit adjustment of the float 60 upon the tube 48 to effect an increase or decrease in the amount of fuel in the tank at the time the valve closes, thereby providing means for varying the reserve supply of fuel when desired. The casing 46 is provided with a screw cap 69 having upon the lower face thereof a washer 70 engaging the upper peripheral edge of the casing for the purpose of rendering the latter air-tight. A strainer 71 is mounted in the casing 46 and is connected with a plate 72 screwed upon the inner end of the conduit 17 to prevent the passage therethrough of any foreign matter.

The invention may be assembled as a unit and screwed into proper position as shown, after which the tube 17 is screwed into the casing 46 and the strainer 71 then placed thereon.

In use, this device operates to give notice when the supply of fuel in the tank 16 has decreased to a predetermined minimum. When the tank is filled, the float 60 holds the yoke 64 up against the bottom of the tube 48. When the level of fuel descends far enough, the float begins to descend and as the withdrawal of fuel continues, the float descends still farther until the valve 50 which is carried thereby seats itself and cuts

off the further passage of fuel from the tank to the tube 48. Thereupon the gas engine or other apparatus being operated by the fuel ceases to function. By this means the operator is informed of the fact that his fuel is low. If a supply of fuel is at hand, he naturally refills the tank, but if none is at hand as in the case of an automobile on the road, the operator removes the cap 69 from the casing 46 and lifts the valve stem 51 manually, hooking its upper end into the bifurcated extremity of the spring holder 53 as shown in Fig. III, thus supporting the valve 50 out of contact with its seat. The balance of the fuel in the tank may then be drawn upon by the engine to propel the automobile to a filling station, but before the vacuum system can be operated to lift fuel, the cap 69 must first be replaced. This constitutes an important advantage of the invention as it guards against the admission of dust and dirt into the apparatus as well as a possible loss of the cap 69, should the automobile happen to be in the hands of careless or absent-minded drivers. When the tank is again filled, the float 69 rises, carrying with it the valve stem 51 until the latter releases itself from the holder 53, which being of resilient material, springs back into the position in which it is shown in Fig. II, where it will not interfere with the movement of the stem 51 in either direction.

While I have shown the invention as being connected with the vacuum fuel feed system of an internal combustion engine, it will be understood that any suitable form of aspirator may be connected with the casing 46, and that the device is applicable for other purposes than that specifically pointed out herein.

When the engine stops for lack of fuel, it may be cranked by hand or by a self starter after the valve 50 is opened, until sufficient fuel is fed to the carburetor to permit the engine to run on its own power.

Having thus described my invention, what I claim as new and desire to secure by Letters Patent is:—

1. A liquid control device comprising a closure arranged to be connected with an aspirator and adapted to be inserted within a liquid holding receptacle, said closure having a liquid inlet passageway sealed by the liquid in the receptacle, means partially within the closure arranged to automatically close said passageway when the liquid in the receptacle falls below a predetermined level, and a holder for said last mentioned means serving when connected therewith to prevent the closing of the passageway when the liquid in the receptacle stands below said level, said means being automatically released from said holder when the liquid in the receptacle rises above said level.

2. A liquid control device comprising an

air tight tube arranged to be connected with an aspirator and adapted to be inserted in a liquid holding receptacle, said tube having an inlet passageway normally sealed by the liquid in the receptacle, means partially within the tube arranged to automatically close said passageway when the liquid in the receptacle falls below a predetermined level, a holder for said last mentioned means serving when connected therewith to prevent the closing of the passageway when the liquid in the receptacle is below said level, said means being automatically released from said holder when the liquid in said receptacle rises above said level, and a member normally closing an opening in said tube and permitting access thereto.

3. A liquid control device comprising a closure arranged to be connected with an aspirator and adapted to be inserted within a liquid holding receptacle, said closure having an inlet passageway sealed by the liquid in the receptacle, a float controlled valve for said passageway having a stem disposed within the closure, said valve being adapted to automatically effect the closing of said passageway when the liquid in the receptacle falls below a predetermined level; and a holder for said stem serving when connected therewith to prevent said valve from closing said passageway when the liquid in the receptacle falls below said level, said stem being automatically released from said holder when the liquid in the receptacle rises above said level.

4. A liquid control device comprising a closure arranged to be connected with an aspirator and adapted to be inserted within a liquid holding receptacle, said closure having an inlet passageway sealed by the liquid in the receptacle, a float controlled valve for said passageway having a stem disposed within the closure, said valve being adapted to automatically effect the closing of said passageway when the liquid in the receptacle falls below a predetermined level, and a yieldable holder for said stem normally out of position to be engaged thereby and movable to connect with the stem to prevent said valve from closing said passageway when the liquid in the receptacle is below said level, said stem being automatically released from said holder when the liquid in the receptacle rises above said level, said holder, when the stem is disconnected therefrom being automatically returned to normal position.

5. A liquid control device comprising a closure insertible in a liquid holding receptacle and provided with inlet and outlet passageways, said outlet passageway being adapted for connection with an aspirator, a valve for controlling said inlet passageway, means partially within the closure for main-

taining said valve open when the liquid in the receptacle stands above a predetermined level and manually controlled means for setting the valve in open position from which position it is automatically released when the liquid rises above said level.

6. A liquid control device comprising a closure insertible in a liquid holding receptacle and provided with inlet and outlet passageways, said outlet passageway being adapted for connection to an aspirator, a valve for controlling said inlet passageway, means upon the closure for maintaining said valve open when the liquid in the receptacle stands above a predetermined level, manually controlled means within the closure for setting the valve in open position from which position it is automatically released when the liquid rises above said level, and a removable member upon said closure for rendering said manually controlled means accessible.

7. A liquid control device comprising a closure insertible in a liquid holding receptacle and provided with inlet and outlet passageways, an aspirator connected with said outlet passageway, means carried by the closure arranged to automatically close said inlet passageway when the liquid falls below a predetermined level, and a holder within said closure for said last mentioned means serving when connected therewith to prevent the closing of said inlet passageway, said means being automatically released from said holder when the liquid in the receptacle rises above a predetermined level.

8. A liquid control device comprising a closure insertible in a liquid holding receptacle and provided with inlet and outlet passageways, an aspirator connected with said outlet passageway, means carried by the closure arranged to automatically close said inlet passageway when the liquid falls below a predetermined level, a holder within said closure for said last mentioned means serving when connected therewith to prevent the closure of said inlet passageway, said means being automatically released from said holder when the liquid in the receptacle rises above a predetermined level, and a removable member upon said closure adjacent said holder for rendering the latter accessible.

9. A liquid control device comprising a closure insertible in a liquid holding receptacle and provided with inlet and outlet passageways, means carried by the closure arranged to automatically close said inlet passageway when the liquid falls below a predetermined level, and a holder within said closure for said last mentioned means serving when connected therewith to prevent the closing of said inlet passageway,

- said means being automatically released from said holder when the liquid in the receptacle rises above a predetermined level.
10. A liquid control device comprising a receptacle, a closure connected with and extending into said receptacle and having liquid inlet and outlet passageways therein, an aspirator connected with said outlet passageway, means carried by the closure arranged to automatically close said inlet passageway when the liquid falls below a predetermined level, and a yieldable holder within said closure for said last mentioned means serving when connected therewith to prevent the closing of said inlet passageway, said means being automatically released from said yieldable holder when the liquid in the receptacle rises above a predetermined level.
20. 11. A liquid control device comprising a liquid holding receptacle, a closure insertible in said receptacle and provided with inlet and outlet passageways, an aspirator connected with said outlet passageway, a valve for controlling said inlet passageway, means upon the closure for maintaining said valve open when the liquid in the receptacle stands above a predetermined level, said valve being adapted to close automatically when the liquid falls below said level, and manually controlled means wholly within the closure for setting the valve in open position from which it is automatically released when the liquid rises above said level.
30. 12. A liquid control device comprising a liquid holding receptacle, a closure insertible in said receptacle and provided with inlet and outlet passageways, a valve for controlling said inlet passageway, means carried by the closure for maintaining said valve open when the liquid in the receptacle stands above a predetermined level, said valve being adapted to close automatically when the liquid falls below said level, manually controlled means within the closure for setting the valve in open position from which it is automatically released when the liquid rises above said level, and a strainer for said closure.
40. 13. In a liquid control device, the combination with a liquid holding receptacle, a closure connected with and extending into said receptacle and having inlet and outlet passageways therein, a float controlled valve arranged to automatically close said inlet passageway when the liquid in the receptacle falls below a predetermined level, a stem connected with said valve and projecting into said closure, a holder within the closure serving when connected with said stem to prevent the closing of the valve, said stem being automatically released from said holder when the liquid in the receptacle rises above a predetermined level, and a removable member upon the closure for rendering said stem and holder accessible.
50. 14. In a liquid control device, the combination with a liquid holding receptacle, a closure connected with and extending into said receptacle and having inlet and outlet passageways therein, an aspirator connected with said outlet passageway, a float controlled valve arranged to automatically close said inlet passageway when the liquid in the receptacle falls below a predetermined level, a stem connected with said valve and projecting into said closure, a yieldable holder within the closure serving when connected with said stem to prevent the closing of the valve, said stem being automatically released from said holder when the liquid in the receptacle rises above a predetermined level, and a removable member upon said closure permitting access to said stem.
60. 15. The combination with the vacuum fuel feed system for an internal combustion engine, automatic means for closing the system when the fuel supply reaches a predetermined minimum, manually controlled means for affecting the operation of said last mentioned means, and a removable sealing member for said system, normally rendering said manually controlled means inaccessible.
70. 16. A liquid control device comprising a casing adapted for connection with a liquid holding tank and an aspirator, a removable cover for said casing, a tube extending from the casing, and having an opening in the end thereof, a valve for controlling said opening, a rod connected with said valve and extending through said tube into the casing, a spring holder in the casing adapted to engage said rod to hold it in position to maintain said valve in open position, and a float operatively connected with said rod and valve for raising the same to effect the release of the rod from the holder, said device being adapted for controlling the discharge of liquid from said tank.
80. 17. A liquid control device comprising a casing adapted for connection with an aspirator and having a removable cover thereon, a tube communicating with said casing and extending therefrom, having a liquid inlet opening therein, a valve for controlling the opening, a rod connected with the valve and extending upwardly through said tube into the first mentioned casing, said rod having a laterally bent portion at its upper end, a spring holder in the casing having a notch in the upper end thereof adapted to receive said laterally bent portion of the rod, means for guiding the rod within said tube, and a float for raising said rod and serving to effect the release of said laterally bent portion from said spring holder.

18. A liquid control device comprising a casing adapted for connection to a liquid supply tank, a tube extending from said casing and adapted to be inserted in said

erating member being automatically released from said holder when the fuel in the tank rises above said level, and an aspirator connected with said tube.

5 tank, a float controlled valve adapted to prevent the passage of liquid into said tube when the liquid in the tank reaches a predetermined level, an operating member connected with said valve and extending 10 through said tube into said casing, and means within the casing for supporting said operating member in position to prevent the closing of the valve when the liquid in said tank falls below said level, said 15 operating member being automatically released by the action of said float when the liquid in the tank rises above said level.

22. In a fuel control device, the combination of a fuel supply tank, a tube projecting

19. In a liquid control device, the combination with a liquid supply tank, a casing connected therewith, a tube extending 20 from said casing into said tank, a float controlled valve adapted to prevent the passage of liquid through said tube when the liquid in the tank falls below a predetermined 25 level, a manually controlled operating member connected with said valve and extending through said tube into said casing, a holder within the casing for supporting said operating member in position to prevent the closing 30 of said valve, a removable air-tight cover for said casing by which the operating member is rendered accessible, and an aspirator connected with said casing, the replacement of said cover being necessitated 35 to insure the functioning of the aspirator.

22. In a fuel control device, the combination of a fuel supply tank, a tube projecting therein, a float controlled valve for preventing the passage of fuel through the tube when the fuel in the tank falls below a predetermined level, an operating member connected with said valve and extending into said tube, and a holder for said operating member adapted to re-

40 leaseably support the same in position to prevent the closing of said valve when the fuel in the tank falls below said level, said operating member being automatically released from said holder when the fuel rises above said level, and an aspirator connected with said tube, and a strainer for preventing the passage of foreign matter to said aspirator.

22. In a fuel control device, the combination of a fuel supply tank, a tube projecting

45 21. In a fuel control device, the combination of a fuel supply tank, a tube projecting therein, a float controlled valve adapted to prevent the passage of fuel through said tube when the fuel in the tank falls below a predetermined level, an operating member for 50 said valve extending into said tube, a holder for said operating member adapted to support the same in position to prevent the closing of said valve when the fuel in the tank 55 falls below said predetermined level, said op-

23. In a fuel control device, the combination of a fuel supply tank, a tube connected therewith and projecting therein, a float controlled valve for preventing the passage of fuel through said tube when the fuel in the tank falls below a predetermined level, an operating member for said valve, a holder for said operating member adapted to support the same in position to prevent the closing of the valve when the fuel in the tank

- controlled operating member connected with said valve and extending into said casing, a holder within said casing for said operating member adapted to retain the same in position to prevent the closing of said valve when the fuel in the tank falls below said level, an aspirator connected with said casing, and a sealing member for said casing normally rendering said operating member inaccessible, said sealing member being removable to permit the setting of the operating member upon said holder, and serving when removed to prevent the functioning of said aspirator.
26. In a fuel control device, the combination of a fuel supply tank, a closure connected with the tank and extending therein, a removable sealing member for said closure, an aspirator connected with the closure, means normally permitting the flow of fuel through the closure when the aspirator is in operation, said means serving to automatically prevent the passing of fuel through the closure when the fuel falls below a predetermined level, and manually controlled means for establishing communication between the closure and said tank after the fuel has fallen below said level, said manually controlled means being automatically released when the fuel in the tank rises above said level, said sealing member normally rendering said manually controlled means inaccessible, and serving when removed to prevent the functioning of said aspirator.
27. In a fuel control device, the combination of a fuel supply tank, a closure extending therein to a point adjacent the bottom of the tank, a removable sealing member for said closure, an aspirator connected with said closure, float controlled means for preventing the passage of fuel through said closure when the fuel in the tank falls below a predetermined level, and manually controlled means for setting said float control means in position to permit passage of fuel through said closure, said manually controlled means being automatically released when the fuel in the tank rises above said predetermined level, said removable member normally rendering said setting means inaccessible, and serving when removed to render said aspirator ineffective.
28. In a fuel control device, the combination with the vacuum fuel feed system of an internal combustion engine and the fuel supply tank therefor, of a closure extending into said supply tank and communicating with said fuel feed system, means normally permitting the passage of fuel through said closure and automatically stopping its flow when it falls below a pre-determined level, and means within the closure for setting said last mentioned means in position to permit the flow of the fuel through the

closure, after it has descended to said level, 65 said setting means being automatically released when the fuel in the tank rises above said level and being accessible only upon the removal of a sealing member for the closure.

29. The combination of a liquid holding tank, a tube projecting therein having an inlet passageway adapted to be sealed by the liquid in the tank, an aspirator connected with the tube, means adapted to automatically close said passageway when the liquid in the tank reaches a predetermined level, said means being manually adjustable to open the passageway and adapted to be automatically released from adjusted position 80 when the liquid rises above a predetermined level within the tank and a removable sealing member for said tube normally rendering said manually controlled means inaccessible.

30. The combination of a liquid holding tank and a suction producing apparatus for drawing the liquid from the tank, means movable automatically for preventing the flow of liquid from the tank when the supply reaches a predetermined minimum, manually controlled means for effecting operation of said last mentioned means to permit the continued withdrawal of the liquid from the tank and a removable sealing member for said suction apparatus normally rendering said manually controlled means inaccessible.

31. The combination of a liquid supply tank and means for forcing liquid therefrom, means connected with said last mentioned means for stopping the flow of liquid from the tank when it reaches a pre-determined level therein, manually controlled means connected with the last mentioned means and adjustable to permit the continued withdrawal of the liquid from the tank and a member normally rendering said manually controlled means inaccessible and movable to permit the operation of the same, said movable member rendering said liquid forcing means ineffective except when in normal position.

32. The combination of a liquid supply tank and means for forcing liquid therefrom, means connected with said last mentioned means for stopping the flow of liquid from the tank when it reaches a predetermined level therein, manually controlled means connected with said last mentioned means adjustable to permit the continued withdrawal of the liquid from the tank, a holder for supporting said manually controlled means in adjusted position, from which it is automatically released when the liquid in the tank again rises above said predetermined level and a member normally rendering said manually controlled means inaccessible and movable to permit the man-

ual operation of the same, said removable member rendering said liquid forcing means ineffective except when in normal position.

33. In a fuel feed system, a tank, a tube 5 adapted to extend downwardly into said tank, said tube being provided with an enlarged head mounted in a hole in the top of the tank, a valve controlling communica-

tion between the tank and the lower end of the tube, and an annular float surrounding 10 said tube and operatively connected to said valve, the outside diameter of said float being less than the outside diameter of said head.

In testimony whereof, I affix my signature. 15

FRANCIS JERDONE, JR.
